UNITED STATES PATENT OFFICE.

EDWIN GEUSSENHAINER, OF NEUMÜNSTER, GERMANY.

SATE.

1,103,139.

Specification of Letters Patent. Patented July 14, 1914.

Application filed January 11, 1912. Serial No. 676,700.

To all whom it may concern:

Be it known that I, EDWIN GEUSSENHAINER, a citizen of the United States of America, residing at Friedrichstrasse F, 5 Neumünster, in the Province of Schleswig-Holstein, Prussia, Germany, have invented certain new and useful Improvements in Baths, of which the following is a specification.

10 This invention consists in producing a bath of a particular form or shape especially of the cast iron kind.

It is now necessary in the manufacture of baths to adapt their shapes according to 15 whether they are to be let into the wall or left free, or covered with tiles or the like, so that it is necessary to prepare various designs of bath for instance, for left hand corners, right hand corners, flat walls, niches, 20 or for being covered in or let into the wall or free to stand alone. In baths as now manufactured, the question of sloping head ends and also the position of the outlet are matters which must receive consideration.

25 The locations in which a single design of the usual bath can be placed are very limited, and the large number of patterns it is consequently necessary to stock owing to the variety of baths made is expensive and

30 troublesome and leads to much waste of castings. These drawbacks are obviated by the present invention according to which the shape of the bath is so designed, and the applications of it therefore so multiplied, that it will fit into any corner and niche in the wall or can be surrounded by a covering or allowed to stand alone. These objects are attained chiefly by providing the unsymmetrical bath (bathing-tub) with a rectangular

40 horizontal rim, which is symmetrical with the principal horizontal axes of the bath. The corners of said rim R only slightly rounded and each substantially to the same extent and the extreme outer edge

45 of the rim is slightly curved downward, in order that the bath rim may unite well with the wall surface or with the tiles thereon, no special shape of masonry being necessary for the corners of the wall.

An example of the bath is shown in the 50 accompanying drawings, in which—

Figure 1 is a longitudinal section, and Fig. 2 a plan. Figs. 3 and 4 are cross sections of the bath edge respectively when let into the wall and with a covering. 55

The rim a of the bath is formed symmetrical about the two axes (Figs. 1 and 2) so that the bath can accurately fit into any recess or niche as may be desired. The corners b are only slightly rounded off to substantially the same degree so that they will be completely overhung either by the wall or the wall tiles, without the necessity of specially shaping the wall corners. The rim a is essentially level and of substantially the 65 same width and meets evenly the wall along its curved edge c. This edge c (Figs. 3 and 4) is only very slightly rounded or curved outwardly and downwardly throughout so much of its width as is covered by the super- 70

ior thickness of the wall covering d or the tiles e. This construction permits any of the

75 sides of the bath as may be desired, to be

let into the wall making a satisfactory joint or corner therewith or said sides can be cov-

ered in with tiles or the like, resulting in the

advantage already set forth.

I claim:

1. A bath for universal installation having its rim periphery substantially rectangular in shape and with its edges curved outwardly and downwardly and with the intermediate portion of the rim flat, the meeting points of adjacent rim edges being curved, the length of the curves in cross section being within the planes provided by the thickness of normal wall tiling, whereby the bath may be installed with its rim totally or partially exposed at will with the curved portion overlapped by the tiling when the 90 bath is installed with its rim partially exposed.

2. A bath for universal installation having its rim periphery substantially rectangular in shape and with its edges curved outwardly and downwardly and with the intermediate portion of the rim flat, the meeting points of adjacent rim edges being

curved, the length of the curves in cross section being within the planes provided by the thickness of normal wall tiling, whereby the bath may be installed with its rim totally or partially exposed at will with the curved portion overlapped by the tiling when the bath is installed with its rim partially exposed, the cross sectional configuration of the curved and flat portions of the

rim being similar on each of the rectangular 10 edges of the bath.

In testimony whereof I have affixed my signature in presence of two witnesses.

EDWIN GEUSSENHAINER.
